KNITTED FABRIC AND METHOD OF MAKING
SAMEJoseph Gerson, Newark, N. J., assignor to Harry
Rubin, New York, N. Y.

Application June 7, 1940, Serial No. 339,262

6 Claims. (Cl. 66—170)

This invention relates to improvements in the knitting art and has particular reference to a trimming in the nature of a fringe for use on drapes, bedspreads and the like, and the method 5 of making the same.

Trimmings of the general character of the present invention have been made heretofore wherein the strands comprising the tassels are grouped or bunched by an operator, after the 10 machine knitting has been completed, and portions of adjacent groups are then either tied in a knot or are bound together by tying a thread thereabout to form the tassels. This manual operation consumes considerable time and therefore materially increases the cost of production. 15

In accordance with the present invention, it is proposed to eliminate much of the manual labor in the production of a trimming by knitting an elastic thread or threads under tension in such 20 manner that a loop of said thread will encircle each group of strands or yarns that comprises a tassel of the trimming, and then, after the knitting operation is completed, severing said thread on opposite sides of the groups of strands 25 constituting a tassel, so that loops embracing the encircled strands will contract about the latter and thus tie them together to complete a tassel.

The inventive idea involved is capable of receiving a variety of expressions one of which, for 30 purposes of illustration, is shown in the accompanying drawing wherein:

Figure 1 is a fragmentary plan view of a knitted fabric, such as a trimming or fringe, showing the position thereof while it is being 35 fabricated on a knitting machine.

Figure 2 is a similar view of the trimming after being removed from the machine and preparatory to final operations of severing the elastic threads and the lower ends of the tassels.

Figure 3 is a similar view of the completed 40 fabric.

Figure 4 is a section on the line 4—4 of Figure 2.

Figure 5 is a section on the line 5—5 of Figure 3, and

Figure 6 is an enlarged fragmentary perspective view, showing an elastic thread looped about the groups of strands which comprise a tassel.

The trimming of the present invention may 50 be made on a standard type of knitting machine and, in accordance with the usual procedure, a plurality of closely adjacent wales and filler threads 7 and 8, respectively, are knitted to form the edging 9. At the same time, other elongated 55 strands or filler threads 10 are looped into the

edging 9 at spaced intervals, as indicated at 11, and at their opposite ends are caught by one or more wales 12.

At a point near the edging 9, and paralleling the same, strands 10 of adjacent groups of filler threads are stitched together or gathered by one or more wales 13 so that strands of said groups will converge downwardly from the edging 9, as shown at 14, to form the upper end of a tassel. Loops 15 of each thread or wale 13 encircle the 10 gathered portions of said groups of strands, as best illustrated in Figures 4 and 6.

The threads 13 are, according to the invention herein disclosed, made of any suitable elastic material and, during the knitting operation, these 15 threads are kept under tension or stretched so that the loops 15 will be expanded. Upon completion of the knitting operation, the thread or threads 13 are severed, as indicated at 16, in Figure 2, adjacent to and on opposite sides of the 20 two groups of strands 10 which comprise a tassel and when so severed, the loops 15 will contract about said groups to bind together and bunch the strands thereof, as illustrated in Figure 5.

As will be seen from Figure 6, the loops of the 25 stitches extend to the rear of the groups of strands 10 and, due to this, the tendency is for the extremities of the severed ends to be drawn to the rear of the tassel (see Figure 5) by said loops and thus be invisible when the trimming is in use. The elasticity of the threads 13 is such 30 that the severed ends will be securely bound by the contraction of the loops 15 and, therefore, will not become loosened. As a final step in the 35 completion of the trimming, the ends of the groups of strands 10 forming the tassels are severed along the line indicated at 17 (Figure 2) adjacent the wales 12 so that the lower extremities of the strands constituting said tassels will be unattached to each other.

What is claimed is:

1. A trimming for drapes and the like comprising a plurality of loose strands arranged in groups, and an elastic binding element embracing 45 each group of strands between the ends thereof to form a tassel.

2. A knitted trimming for drapes and the like comprising an edging, a plurality of groups of strands extending from said edging, and elastic 50 binding elements embracing portions of adjacent groups to form tassels.

3. A knitted trimming for drapes and the like comprising an edging, a plurality of groups of strands extending from said edging, and knitted 55

elastic stitches embracing portions of adjacent groups to form tassels.

4. The method of knitting a trimming for drapes and the like which comprises forming into groups a plurality of loose yarns extending from an edging by looping a continuous elastic thread under tension about said groups, and thereafter severing said elastic thread on opposite sides of each loop thereof which embraces a formed group so that said loop will contract and bind the yarns of its group.

5. The method of making a trimming for drapes and the like which comprises knitting an edging, securing a plurality of groups of loose 10 yarns to said edging at spaced intervals, utilizing an elastic thread under tension to connect adja-

cent groups of said yarns at points spaced from said edging by looping said thread about said groups, and thereafter severing said thread on opposite sides of the loops formed about said groups.

6. The method of making a trimming for drapes and the like which comprises knitting a plurality of spaced wales and filler threads to form an edging, looping into said edging a plurality of spaced groups of loose threads, joining 10 adjacent portions of said groups by an elastic wale which is looped about said portions while under tension during the knitting operation, and thereafter severing said wale on opposite sides of the loop which embraces each of said portions. 15

JOSEPH GERSON.
